SUPPORT FOR CONNECTION CORDS OF
ELECTRIC IRONS

Edward S. Halsey, North Miami, Fla.

Application November 24, 1939, Serial No. 305,970

5 Claims. (Cl. 243—51)

This invention relates to supports for the extension cords of electric irons of that type adapted to be attached to a table top or ironing board.

The main object of this invention is to create a device of the character stated which will possess, in addition to the common supporting functions of prior devices, the advantages and novel structural improvements hereinafter recited, whereby to provide a better device at lower cost and one that can be sold at a popular price, and is adapted to automatic machine production methods.

My detailed objects are:

First, by making its upstanding structure, or arm, of triangular truss form, comprising a light stiff wire bent in inverted V-form with its two divergent bottom ends yoked together (through short, close-wound spring couplings) by a horizontal block cross-piece constituting its base and the third side of said triangle, I am able to provide a neater, more efficient, frictionless, noiseless and trouble-free structure at lower cost; and one rigid against side sway from angular attaching plug pull or other disturbing side stresses, while it is free to rock through an angle of 180° on its base springs, or 90° either forward or backward, with its supported cord, allowing unrestricted travel of the iron to and beyond the end of the board; and by virtue of the light, graduated tension of the helical springs, the arm is automatically restored to its neutral vertical position upon relaxation of cord tension.

Second, the improved form of base clamp shown made from thin, mild spring wire, shaped into a U-like configuration by two intermediate right-angle bends which direct its end extremities into a parallel pair of legs yoked together by the straight center portion of the wire and then curling this yoked end of the legs downwards and circularly up towards the center portion of the extended legs forming a yoked pair of clamping loops with a broad base so adapted that said yoke clamps the under side of the table when the straight portion of said two legs (fixed in the base block) are sprung over the top edge of the table, thus providing a most efficient, inexpensive clamping means for this purpose, which by virtue of the high flexing quality of these wide circular clamping loops of soft spring wire, is more readily fitted and applied to any and all kinds and thicknesses of ironing boards than any previous clamp offered for the purpose.

Third, by a novel attaching means for said clamp to its base block, the main flat frame struc-

ture can be conveniently stacked separate from its side protruding clamp to facilitate condensed packing of a dozen to a carton for commercial shipment, so provided that the recipient can 5 easily and quickly attach each clamping spring to its base block before putting it into use, as the two end extremities of its wire legs are doubled back on themselves a short distance by accurate machine molding to form elastic tapering wedge-shaped extremities which are readily inserted by hand in a corresponding pair of socket holes in the base block and then are driven firmly home into their sockets by a few taps of a light hammer on the back-turned projecting ends 10 of the wire.

Fourth, an economical, novel and effective means of firmly socketing the small round bottom ends of the V-arm in the larger top ends of the short upright helical springs (which are economically machine cut from long commercial springs). This is accomplished by doubling back 20 the bottom ends of the arm in the same manner, and by the same machine, as are the ends of the spring clamp next above described, and by simultaneously machine-pressing the elastic wedge-shaped terminals of the V-arm thus formed down into the top ends of their block-mounted spring sockets so as to form a firm, sightly and low-cost junction.

Fifth, to prevent pinching, rubbing, chafing and sharp bending of the cord at its point of engagement with the apex of its traveling suspension arm, I have developed the simple, inexpensive and effective staggered, double-hooked wire 30 cradle shown, having two widely separated bearing loops around its horizontal axis, formed at the apex end of the wire supporting arm, so constituted that the central portion of the cradle wire forms a bridging cross-link between its two 35 bearings beneath said axis and the cord while riding in said cradle, preventing wear of the cord, and the two bearing loops of the cradle when 40 turning bear against the two upright wires of the arm holding it and its supported cord centrally away from said arm preventing rubbing of 45 the cord.

Sixth, to prevent rubbing and chafing of the cord against the lower parts of the structure or 50 the edge of the ironing board under such conditions as often exist when the cord-connecting outlet happens to be near or below the level of the ironing board, allowing the slack cord to drag over the edge of the board when the travelling 55 arm oscillates, I have devised the simple anchor

stud shown, centrally projected from the back side of the base block so that the cord can be conveniently hooked under it in either a forward or backward direction as may be required effectively preventing any rubbing action of the cord.

With the foregoing and other objects in view, the nature of which will appear as the description proceeds, the invention consists of the construction, combination and arrangement of parts thereafter fully described and claimed, and illustrated in the accompanying drawing, wherein:

Figure 1 is a view in side elevation illustrating the manner in which the holder is secured to an ironing board and the manner in which the connection cord of the iron is connected to the holder;

Figure 2 is a view partly in vertical section and partly in rear elevation of the holder;

Figure 3 is a view in side elevation of the lower portion of the holder;

Figure 4 is a view partly in side elevation and partly in vertical section illustrating the manner in which the arm is secured to the springs and the manner in which the clamp is secured to the base, and

Figure 5 is a perspective view illustrating the formation of the cradle of the holder and the manner in which the cradle is mounted upon the arm.

Referring in detail to the drawing, particularly to Fig. 1, 1 designates an ironing board, 2 an electric iron and 3 the connection cord of the iron.

The cord holder comprises a base 4 which is of narrow elongated formation and which may be made of wood or any other material suitable for the purpose. The base 4 which rests directly upon the ironing board 1, is secured in place by a spring clamp 5, and carries an upwardly-extending cord-suspending arm 6. The base 4 is provided near its ends with sockets 4^a, which are perpendicular to the flat lower side of the base and which open through the upper side of the base. The base 4 is also provided with downwardly and rearwardly inclined sockets 4^b, which open through the rear side of the base.

The arm 6 is of substantially inverted V-form and is made of thin mild spring wire. The arm 6 is connected to the base 4 by helical springs 7. The side members, 6^a, of the arm 6 are smaller diametrically than the corresponding inner dimension of the springs 7. The lower end portions of the side members 6^a are bent upwardly to provide wedge-shaped members 6^b, which are forced into the upper end portions of the springs 7 to secure the arm 6 to the springs. The wedge-shaped members 6^b may be readily forced into the springs 7 by applying pressure to the upwardly-facing free ends of the wedge-shaped members.

The springs 7 are closely wound and extend for a short distance above the base 4. The springs 7 are secured to the base by having their lower end portions threaded into the sockets 4^a of the base. If desired the springs 7 may have a drive fit in the sockets 4^a, and may be driven into the sockets while the wooden base is moist and spongy, whereby fibrous portions thereof will be forced between the convolutions of the springs anchoring them securely by dry shrinkage. The springs 7, while constantly tending to hold the arm 6 in an upright position, permit the arm to swing forwardly or rearwardly through an angle of 90° during the use of the iron 2.

The clamp 5 comprises vertically arranged spring loops 5^a, shanks 5^b extending forwardly from the upper ends of the spring loops, and a cross bar 5^c connected to the lower ends of the spring loops. The clamp 5 is formed from a single length of spring wire, and the front end portions thereof are bent to provide wedge-shaped members 5^d which are driven into the sockets 4^b of the base to connect the spring to the base. The wedge members 5^d may be readily driven into their sockets by applying force to their rearwardly-facing free ends. Due to the inclination of the sockets 4^b, the shanks 5^b incline downwardly and rearwardly from the base 4. The spring loops 5^a embrace the edge of the ironing board 1. The cross bar 5^c contacts with the lower side of the ironing board, and the shanks contact with the upper side of the ironing board. The contact between the clamp 5 and the ironing board is such as to hold the base on the ironing board against accidental movement while the iron 2 is being used. The clamp 5 may be readily detached from the base 4 to permit the base and its arm 6 on the one hand, and the clamp on the other, to be arranged compactly for shipment or storage. The clamp 5 may be readily connected to the base 4 by the dealer or purchaser.

The connection cord 3 which extends through the upper end of the arm 6, is connected to the arm by a cradle 8 which is preferably made of wire and which is rockably connected to the cross bar 6^c of the arm. The cradle 8 comprises side members 8^a which extend in opposite directions from the cross bar 6^c and which are offset laterally with relation to each other. Hooks 8^b carried by the side members 8^a are located at opposite sides of and extend inwardly from said members. The cradle 8 is provided centrally between its ends with bearing loops 8^d through the medium of which it is rockably suspended from the cross bar 6^c. The bearing loops 8^d contact with the inner surfaces of the sides 6^a of the arm 6 to hold the cradle 8 against lateral play with relation to the arm. The connection cord 3 passes through the hooks 8^b and below and in contact with that portion of the cradle which extends between the bearing loops 8^d and which is located below the cross bar 6^c. The cradle 8 holds the connection cord 3 against endwise movement with relation thereto, and holds the connection cord out of contact with side members 6^a and cross bar 6^c of the arm 6. An anchor stud 9 is secured by the rear side of the base 4 centrally between the ends of the latter.

In practice the base 4 is mounted upon an ironing board. The spring clamp 5 is applied to the edge of the board and the connection cord is engaged with the cradle 8. The spring clamp 5 positively holds the base 4 against rocking or bodily movement with relation to the ironing board. As the iron is moved away from the base 4, the arm 6 swings in the direction in which the iron is being moved, tensioning the springs 7. As the iron is moved in the direction of the base 4, the springs react and move the arm 6 in the direction of its normal or vertical position, so as to support any slack in that portion of the connection cord located between the iron and the upper end of the arm 6 that may occur when the iron is close to the base. The springs 7 are so tensioned that their resistance to the movement of the arm 6 is hardly perceptible to the ironer. As the arm 6 swings, the cradle 8 rocks freely in the upper end of the arm. As the

cradle 8 holds the connection cord from contacting with the arm 6, and the elongated dual support of the cradle prevents repeated short bending and injury of that supported section of the cord within its embrace, its life is prolonged and the insulation thereof will not be subjected to abrasion or wear. As a further protection, the cord may be looped under the anchor stud 9 when the outlet is located at such a point with reference to the ironing board as to cause that portion of the cord located rearwardly of the arm 6 to sag and rub up and down against the edge of the ironing board or to pull sideways.

Having described my invention, what I claim is:

1. A holder for the connecting cord of an electric iron comprising a horizontal base, a substantially parallel pair of distantly separated helical retrieving springs projecting perpendicularly from said base with their base ends rigidly fixed thereto, an upwardly projected arm having upwardly converging side members connected together at their upper ends and having their lower ends securely fixed to the two projecting ends of said springs, means for connecting the cord to the upper end of said arm, and a clamp fixed to said base for securing the base to an ironing board.

2. A holder as described in claim 1, wherein the clamp is made of spring wire and comprises vertically arranged loops, shanks extending for-

wardly from the upper ends of the loops and connected to the rear side of the base and occupying a downwardly and rearwardly inclined position with relation to the base, and a cross-bar connected to the lower ends of the loops.

5 3. A holder as described in claim 1, wherein the lower end portions of the side members of the arm are bent to provide wedge-members, said wedge-members extending into the upper ends of the springs to secure the arm to the springs.

10 4. A holder as described in claim 1, wherein the base is of narrow elongated formation, wherein the base is provided in its upper side with sockets in which the lower ends of the

15 springs are secured, wherein the base is provided in its rear side with sockets, and wherein the clamp has wedge-shaped ends fitting in said last sockets to secure the clamp to the base.

20 5. A holder as described in claim 1, wherein the means for connecting the cord to the arm comprises an elongated cradle extending through the upper end of the arm, the cradle being terminally provided with cord-receiving elements, and the cradle being provided between its ends with bearing loops suspending from the cross bar and contacting with the inner surfaces of the side members to hold the cradle against lateral movement with relation to the arm.

EDWARD S. HALSEY.
